PAPER DRINKING CUP AND BLANK FOR
MAKING THE SAMERobert J. Hutt and George A. Hutt, Brooklyn,
N. Y.

Application November 8, 1937, Serial No. 173,318

3 Claims. (Cl. 229—1.5)

This invention relates to a drinking cup preferably of conical contour and formed from a paper blank of improved construction and the object is to provide a cup of such conical shape 5 possessing sturdiness with reinforced walls and a heavily reinforced apex portion for effectively eliminating leakage of water or other liquid.

An inventive feature of the formation of such blanks cut, embossed or otherwise formed from 10 sheets or strips of paper of suitable quality, is the provision when built up on an appropriate mandrel (forming no part of this invention) in the usual manner, of a multi-ply area or field structure extending upwardly from the point or apex 15 of the conical cup, insuring rigidity and strength as well as high liquid sealing qualities.

As stated, the blanks here shown, are shaped for convenient rolling on a mandrel for high production and similarity, and the cost of said production should be negligible, as little waste occurs in producing the blanks.

Other important features of construction are present which will appear in the description and claims including an initial back fold at the start 25 of the rolling operation of the blank on the above mentioned mandrel, providing a double ply portion and a rounded shoulder for stiffening the leading edge and for providing a wedging action between the major convolutions of the cup blank 30 on said mandrel, or between the mandrel itself and the first major convolution by folding the wing forwardly instead of backwardly on said leading edge.

Fig. 1 shows a series of our improved blanks 35 as cut from a strip of appropriate paper;

Fig. 2 is a side elevation of a completed cup and indicating by dot-and-dash lines, the relative position of the blank with the apex of the cup resting on an index dot where it should rest 40 at the beginning and throughout the rolling of the blank into a complete cup;

Fig. 3 is a partial diagrammatic view showing the condition of the leading edge of the cup blank at the start of forming the cup, including a turned 45 back wing resulting in a double thickness and a shoulder for strength in the wall of the cup and further for assisting in rolling the cup after the major convolutions have been rolled to form major walls of the cup.

50 The blank may be described in detail as comprising a unit 18 preferably cut or embossed in series from a strip of suitable paper, each formed with a straight so-called base line 11 and each provided with an index point 12, spaced inwardly of said base line and from which index a fold

line 13 extends upwardly and outwardly to form an obtuse angle with said base line above the intersection therewith, this fold line is preferably embossed, and forms a hinge for a wing to be described.

5 Directly below the index point of the blank and beginning on the vertical line of that index, is an arcuate severance line 14 extending across through the base line 11, to partially free from the lower right hand corner of the blank 10 an 10 adhesive carrying sealing head 15 thus leaving an integral neck 16, and partially pointed terminal 18.

At the beginning of the rolling construction of the cup, a triangular reinforcing wing 17 is turned 15 back from the folded line 13, from the severed line 14, (Fig. 3) and is drawn under the first convolution of the major wall of the cup after which the second convolution of the cup wall covers the reinforcing portion, thus forming a 20 thin wedge between the overlapping main walls of the cup to prevent slippage during the application or spiraling of the sealing head 15 around the downwardly diminishing side walls to the apex of the cup for forming a multi-ply wall offering a rigidly sealed structure against leakage 25 and collapse.

Referring to Fig. 1 of the drawing an arcuate line of adhesive 19 is applied to the blank near to and in parallelism with the lower or trailing edge 20, of the blank and is continued into the sealing head 15 to join a somewhat wider cross line 21 for sealing the walls of the cup and sealing the convolutions of the head 15 in the finishing operation of the cup structure.

35 What we claim is:—

1. A blank for forming paper drinking cups having a quadrantal outwardly curved side edge and a lower upwardly curved edge connected by a straight base-line through irregularly curved 40 edges, said blank also having, an index on its surface from which a straight fold line rises at an angle to connect with said base line; said blank also having a severed arcuate line starting from slightly below said index and extending horizontally to said base line for forming a partially free sealing head at the lower right corner of said blank, and an arcuate line of adhesive applied to the blank near and in parallelism with the said lower arcuate edge of said blank and terminating within the sealing head in a joint with a vertically disposed cross of adhesive extending short of the upper and lower edges of said sealing head, said arcuated line of adhesive fixing the overlapping trailing edge of the blank to the 45 50 55

leading portion of the blank in face to face contact and said adhesive cross of the sealing head acting to secure the convolutions thereof to the apex portion of the cup in spiralling relation and to the extreme point of the cup.

5 2. A cup made from a paper blank, said blank having a general quadrantal form with a convex upper and side edge a concave bottom edge connected by a straight line; the blank having a partially severed sealing head at its lower right corner and above said sealing head; a partially severed wing; a fold line at an edge of said wing for permitting an upward and backward swing thereof into contact with the face of said blank 10 when the formation of the cup begins; providing a two ply wedge located within the convolutions of the cup walls for preventing circumferential slippage of said walls as the finishing sealing operation progresses.

3. A cup made from a paper blank, said blank comprising a general arcuate quadrantal form and a straight edge, said straight edge constituting at its upper part of the cup the leading edge in its formation; a wing folded back from 5 said leading edge for forming a rounded shoulder and a two ply wall beginning at the apex of the cup and which is rolled into the cup structure and finally disposed between the major walls at and slightly above the apex of the cup; a sealing head having a foldable neck from which said head is extended into spiral layers of reinforcing material around and over the apex of the cup including the major walls and the said reinforcing wing portion.
